UNITED STATES PATENT OFFICE.

WILLIAM HUBELI WALDRON, OF NEW BRUNSWICK, NEW JERSEY.

PAPER-COATING MACHINE.

SPECIFICATION forming part of Letters Patent No. 643,574, dated February 13, 1900.

Application filed September 16, 1899. Serial No. 730,709. (No model.)

To all whom it may concern:

Be it known that I, WILLIAM HUBELI WALDRON, of New Brunswick, in the county of Middlesex and State of New Jersey, have invented a new and Improved Paper-Coating Machine, of which the following is a full, clear, and exact description.

My invention relates to paper-coating machines; and its object is to provide a new and improved machine of this character designed either as an adjunct to a paper-making machine or for use as a separate independent machine arranged to uniformly coat or ground the paper on both sides.

15 The invention consists of novel features and parts, as will be fully described hereinafter and then pointed out in the claim.

Reference is to be had to the accompanying drawing, in which the figure is a side elevation 20 of the improvement with parts in section.

In the machine illustrated the paper A' unwinds from a roll B' and passes in a horizontal direction under a delivery device D, arranged to deliver the coating liquid to the 25 upper face of the paper, and the paper then passes in the direction of the arrow a' underneath and around a transverse guiding-roller E' in horizontal alignment with the delivery device D, being thereby turned so that as it 30 passes underneath a second delivery device D', directly above the delivery device D, its other face is coated, as plainly indicated in the drawing.

Each of the delivery devices D D' comprises 35 a trough F, having fountain-rollers D² D³, respectively, mounted therein, and aprons H H' in peripheral contact at their upper ends with the top peripheral faces of the rollers, their lower ends being in close proximity to the opposite faces of the paper A', so that when the rollers are turned and the paper A' travels in the direction of the arrows a' then the coating liquid contained in the troughs F is fed 40 by the rollers D² D³ upon the aprons H H',

from which it flows by its own gravity over 45 the backs of the aprons down upon the opposite faces of the paper. Thus the paper A' is coated on both faces, it being understood that the aprons H H' are wide enough to extend from one side edge of the paper to the other. 50

After the paper leaves the delivery device D' it passes under a roller I and over a brush J, and then it passes over a roller I' and under a brush J' to insure a proper wiping of the colors or pigments into the pores of the 55 paper. The paper then extends between a series of top and bottom brushes K K' and over a roller L, and finally passes between the drawing-rollers, (not shown,) having fans O between the drawing-rollers and the roller L 60 for drying the coated or ground paper to the desired degree before passing from the drawing-rollers to a lathing-machine and a drying-rack, on which the paper is hung up in folds for a final drying. 65

Having thus fully described my invention, I claim as new and desire to secure by Letters Patent—

In a paper-coating machine, a delivery device consisting of a trough under which the 70 paper passes, a roller in said trough, and an apron in peripheral contact with said roller and extending outside the trough into close proximity to the upper surface of the paper, a transverse roller in horizontal alignment 75 with said delivery device, the paper being passed around the roller and returned horizontally over the delivery device, and a second delivery device similar to the first named and located immediately above the same, but 80 reversed in position, the paper being passed underneath said second delivery device, as and for the purpose set forth.

WILLIAM HUBELI WALDRON.
